UNITED STATES PATENT OFFICE.

JOHN WOLF AND ERNEST LESCHHORN, OF CHICAGO, ILLINOIS, ASSIGNEES TO LATHAM MACHINERY COMPANY, A CORPORATION OF ILLINOIS.

STITCHING MACHINE.

Application filed September 12, 1924. Serial No. 737,230.

This invention relates to improvements in stitching machines.

The principal object of the present invention is to provide a simplified stitching machine in which the number of parts used to construct the machine are reduced to a minimum.

A further object of the invention is to provide a very efficient and inexpensive machine 10 in which all of the parts are compactly arranged.

A still further object of the invention is to reduce the number of operative parts of a stitching machine to a minimum and thereby 15 reduce the manufacturing cost and prolong the life of the machine.

These and other objects are accomplished by providing a construction and arrangement of the various parts in the manner hereinafter 20 described and pointed out in the appended claims.

Referring to the drawings Fig. 1 is a front elevational view of our improved form of simplified stitching machine.

Fig. 2 is a cross sectional view of the same taken on the lines 2—2 in Fig. 1.

Fig. 3 is a cross sectional view taken on the lines 3—3 in Fig. 1.

Fig. 4 is a cross sectional view taken on the 30 lines 4—4 in Fig. 3.

Fig. 5 is a detailed view showing a front elevation of the cutting mechanism.

Fig. 6 is a cross sectional view taken on the 35 lines 6—6 in Fig. 1 showing the manner in which the pivoted bracket is mounted and

Fig. 7 is a cross sectional view taken on the lines 7—7 in Fig. 5.

For the purpose of illustration we have 40 shown our improved and simplified stitching machine detachably secured to an arm 10 of the main frame of the stitching machine. The stitcher head is removably secured to the arm 10 by means of three bolts 11 (only one of which is shown). These bolts 11 secure 45 radially extending flanges 13 of the arm 10 to a plate 14. The plate 14 has secured thereto by means of screws 15 a spool supporting bracket 16 which is offset with respect to the longitudinal center of the machine and supports on the upper end thereof a spool of wire 17. The spool is held from accidental rotation by a pressed spring brake 18 which has its outer end curved substantially in the form of a semi-circle 19 for guiding the wire 20 through the usual wire straightener device

and wire spring pressed check mechanism 21. Rotatably mounted within the arm 10 in suitable bearings not shown, is a main drive shaft 22, the outer end of which is provided with a driving pin 23 which is adapted to be seated in a recess 24 formed in a sleeve 25 of the spur gear 26 and butts against one end of a stud 27 as shown at 28. The stud 27 is journalled in a bearing portion 29 of the plate 14. The gear 26 is secured to the stud 27 by means of a pin 30. This arrangement permits the stud 27 to be substantially a continuation of the main drive shaft 22 and at the same time permits the stitcher head to be detached from the arm 10 when it is desired to remove the head. Secured to a reduced portion 31 of the stud 27 is a cam 32. Positioned forwardly of the cam 32 is a second cam 33 which has a wire feeding surface 34 on the outer periphery thereof. These cams 32 and 33 are secured 70 to the stud in any well known manner but preferably by a washer and bolt 33'. Positioned directly above the cam 33 and operatively driven by a gear 35, which is secured to a stud 36 is a second feed cam or roller 37 which is provided with a peripherally projecting wire feeding projection or cam surface 38. The cam surface 38 extends almost completely around the feed roll as clearly shown in Fig. 1. This cam surface 38 cooperates with the feeding surface 34 of the cam 33 and impinges the wire therebetween for feeding the wire through the staple forming and driving mechanism. The stud 36 is mounted in a bearing portion 39 which is 80 formed integrally with a pivoted bracket 40. The bracket 40 is pivoted by means of a shaft 41 to spaced bearing ears 42 formed integrally with the plate 14. The shaft 41 is secured in position by a set screw 43 in threaded engagement with the pivoted bracket 40 and engageable with the shaft 41. The free end of the pivoted bracket 40 is provided with a boss 44 having an aperture 45 extending therethrough which is adapted to loosely receive 100 a threaded bolt 46. The lower end of the threaded bolt 46 is secured in a lug 47 formed integrally with the plate 14 by a pin 48 which extends through a registering aperture in the lug 47 and in the threaded bolt 46. The upper end of the bolt has in threaded engagement therewith a thumb screw 49 which may be adjusted on the bolt 46 for varying the tension on a compression spring 50 mounted on the bolt 46 between the thumb screw 49 and the 110

boss 44 of the swinging bracket 40. The bearing portion 39 of the pivoted bracket 40 extends through a relatively enlarged aperture 51 formed in the plate 14. From the above description it will be noted that by reason of the pivoted bracket 40 and compression spring 50 which normally presses the pivoted bracket in a downward direction, that the feeding surface 38 of the feed roll 37 is thereby resiliently pressed into engagement with the feeding surface 34 of the cam 33 when the wire is gripped between these feeding surfaces in the operation of feeding the wire. The feeding mechanism may be adjusted to feed wires of varying lengths by adjusting the feed roll 37 in such a manner that the wire feeding surface 38 cooperates during a greater or lesser portion of the cycle of operation to impinge the wire during a greater or less arcuate movement of each of these members. This is done by adjusting the roller 37 through the medium of a clamping washer and bolt 51'.

From the above description it will be noted that by positioning one of the feed rollers or feed cams on substantially the main drive shaft we have eliminated a number of intermediate parts and have compactly arranged the feeding mechanism in close association with the main drive shaft and thereby reduced the size of the machine to a considerable extent.

Formed in the front side of the plate 14 is a usual staple forming channel 51" having reciprocally mounted therein a staple former 52 which in turn is provided with a vertically extending channel 53. The channel 53 of the staple former 52 has reciprocally mounted therein a staple driver 54. The staple former 52 is operably driven to form staples by the cam 32 which engages a roller 55 journalled on a pin 55' secured to the rear side and upper end of the staple former. The staple former is normally returned to its uppermost position by the compression spring 56 which is seated in a socket 57 formed in the forward side of the plate 14 adjacent the staple former. The upper end of the compression spring 56 is positioned in a tubular member 58 which normally engages the pin 59 secured to the rear side of the staple former just below the roller 55. The tubular member is reciprocally mounted in the socket 57 as clearly shown in Fig. 2. The staple driver 54 is operatively driven by the usual pitman connection 60 which has one end thereof connected as shown at 61 eccentrically with respect to the axis of the cam 33 and the other end thereof connected as shown at 62 to the upper end 60 of the driver. Co-operating with the staple forming and driving mechanism is the usual anvil 63 and staple supporter 64. The anvil 63 is provided with a wire groove 65 and a compression spring 66 which normally forces the anvil out into the path of the staple form-

ing and driving mechanism. The staple supporter is normally actuated into the path of the staple forming and driving mechanism by means of a compression spring 67. The anvil 63 and the staple supporter mechanism 64 together with the staple forming and driving mechanism, co-operate in a manner well known in the art and a more detailed description of the operation and construction of this mechanism is thought unnecessary.

Adjustably mounted adjacent the staple forming and driving mechanism is our improved wire cutting mechanism which comprises a horizontally adjustable block 68 which has a rearwardly projecting extension portion 69 which is adapted to slidably engage a channel 70 formed in the forward face of the plate 14 for horizontally adjusting the block 68 with respect to the forming and driving mechanism. Mounted in the block 68 and secured therein in any well known manner is the usual cutter tube 71. Secured to the block 68 at the opposite ends thereof and extending upwardly therefrom are two guiding pins 72.

Reciprocally mounted on the guiding pins 72 is a cutter block 73 and secured to the cutter block 73 on the side adjacent the staple forming and driving mechanism by means of a screw 74 is the usual knife 75. Formed on the inner side of and adjacent the top of the cutter block 73 is a projecting flange 76 having thereunder an undercut channel 77. Intermeshing with the flange 76 and undercut channel 77 in a manner to engage and operatively actuate the cutter block 73 is a reciprocally mounted plate 78 which is positioned between the front plate 79 and the main plate 14 of the stitcher head. The front plate 79 is secured to the main plate 14 by means of machine screws 79'.

The front plate 79 is provided with an offset portion as shown at 80 forming a shoulder 80' which forms a stop for the upward movement of the cutter block 73. The cutter block 73 together with its reciprocally mounted plate 78 is normally actuated to its uppermost position by a compression spring 81 which is seated in the recess socket 82 formed on the front side of the plate 14 as shown in Figs. 3 and 4. The upper end of the compression spring 81 is adapted to have seated thereon the head 82' of a spherical headed pin 83 secured to the rear side of the reciprocating plate 78 in any well known manner.

The plate 14 is slotted as shown at 83' so as to permit the spherical headed pin to reciprocate in the operation of severing the wire. The cutting mechanism is actuated to cut the wire by a lever 84 pivoted at 85 to the plate 14. The lever 84 has an upwardly curved portion as shown at 86 which is adapted to be engaged by a cam portion 87 formed as an integral part of the wire feeding cam member 33. The lever 84 is further provided with a laterally projecting portion 88 which

is adapted to have in threaded engagement therewith an adjusting screw 89 and a lock nut 90. The lower end of the adjusting screw 89 is adapted to engage the upper portion 91 of the reciprocally mounted plate 78. By this construction it will be readily seen that during each cycle of operation the cam surface 87 of the cam 33 will engage the free end 86 of the lever 84 and swing said lever in a counter clockwise direction thereby forcing the reciprocating plate 78 downwardly with its cutter block 73 and actuating the knife to cut the wire extending through the cutter tube 71. In connection with adjusting our improved cutter block horizontally with respect to the staple forming and driving mechanism we have provided a series of tapered or conical cavities 92 which are adapted to be engaged by a tapered or conical point 93 of a thumb screw 94. The thumb screw 94 is in threaded engagement with the front plate 79 as shown at 95.

From the above description it will readily be understood that when it is desired to adjust the cutter block 73 together with the cutter tube and block 68, the thumb screw 94 is unscrewed from engagement with one of the cavities 92 of the block 68 and the cutter blocks 73 and 68 are horizontally adjusted by sliding this cutting mechanism in the channels or intermeshing parts 76 and 77 between the lower end of the reciprocating plate 78 in the upper part of the cutter block 73. In this adjustment it will, of course, be understood that the cutter block 68 is adjusted longitudinally of the plate 14 by the rearwardly extending projection 69 engaging the channel 70 formed in the forward face of the plate 14 and when the predetermined adjustment of the cutter block has been determined the thumb screw 94 may be tightened to secure or clamp the cutter block in a relatively fixed position with respect to the staple forming and driving mechanism.

In the operation of the above described device it will be understood that the wire is fed from the spool 17 around the semi-circular guide 19 through the wire straightener and wire checking devices 20 and 21 respectively, where it is engaged by the feeding surfaces 38 and 34 of the feed rollers and feed cams 37 and 33 respectively, through a circular guide tube 96 into the main tube 71 where it passes into the groove 65 formed in the front end of the anvil 63. After the wire is thus fed the cam portion 87 of the wire feeding cam 33 engages the free end of the cam 86 and actuates the lever about its pivot 85, depressing the cutting mechanism through the reciprocating plate 78 against the tension of the compression spring 81, thus causing the wire extending through the tube 71 to be severed adjacent the staple forming and driving mechanism. Simultaneously with the severing of the wire, the cam 32 engages the roller 55 jour-

nalled to the rear side of the staple former 52 and depresses the staple former 52 against the action of the compression spring 56. At the completion of the staple forming operation the staple driver 54 is then actuated through the medium of the pitman connection 60 in driving the staple into the work beneath the head of the stitching machine. It will of course be understood that the anvil 63 is forced from the path of the staple forming and driving mechanism by the staple driver which engages the bevelled front face of the anvil in its downward movement and then the staple supporting member 64 is likewise forced outwardly by the downward movement of the staple driver as it is completing its work in driving the staples.

From the above description it will be readily seen that we have provided a very simple and efficient wire stitching machine and one in which the parts are reduced to a minimum and at the same time we have retained a wide arrangement of adjustments.

It will further be noted that by mounting one of the wire feeding cams of the feeding mechanism on the main drive shaft or an extension thereof that we have provided a construction in which all of the parts are compactly arranged and the number of parts reduced to a minimum thereby reducing the manufacturing cost and also reducing the wear on the operative parts of the machine.

While in the above specification we have described one embodiment which our invention may assume in practice it will of course be understood that the same is capable of modification, and that modification may be made without departing from the spirit and scope of the invention as expressed in the following claims.

What we claim as our invention and desire to secure by Letters Patent is:

1. In a wire stitching machine, the combination with a frame, of a drive shaft mounted in said frame, a wire feeding mechanism mounted on said frame and directly connected to said drive shaft, and a staple forming and driving mechanism positioned directly below said wire feeding mechanism and operatively driven by said drive shaft.

2. In a wire stitching machine, the combination with a frame, of a drive shaft mounted in said frame, a wire feeding mechanism positioned at the forward end of said drive shaft, and a staple forming and driving mechanism positioned directly below said feeding mechanism and operatively driven by said drive shaft.

3. In a wire stitching machine, the combination with a frame, of a shaft mounted therein, wire feeding mechanism mounted on said frame and operatively connected with said shaft, and staple forming and driving mechanism mounted on said frame and operatively connected with said shaft, the medial line

of all the said mechanisms being in the vertical longitudinal plane of the axis of said driving shaft.

4. In a wire stitching machine, the combination with a frame, of a drive shaft mounted in said frame, a wire feeding cam secured to said drive shaft, staple forming and driving mechanism operatively connected to said drive shaft, and a cutting mechanism operatively connected to said cam for cutting the wire fed by said cam.

5. In a wire stitching machine, the combination with a frame, of a drive shaft mounted in said frame, a wire feeding mechanism comprising a plurality of co-operating feeding cams, one of said cams secured to said drive shaft, the other of said cams operatively geared to said drive shaft, staple forming and driving mechanism positioned below and operatively connected to said drive shaft, and a cutting mechanism positioned on one side of said staple forming and driving mechanism and actuated by the cam secured to said drive shaft for cutting the wire fed by said feeding mechanism.

6. In a wire stitching machine, the combination with a frame, of a drive shaft mounted in said frame, a wire feeding mechanism comprising a plurality of co-operating feeding cams, one of said cams secured to said drive shaft, the other of said cams operatively geared to said drive shaft, staple forming and driving mechanism positioned below and operatively connected to said drive shaft, and a horizontally adjustable cutting mechanism positioned on one side of said staple forming and driving mechanism and actuated by the cam secured to said drive shaft for cutting the wire fed by said feeding mechanism.

7. In a wire stitching machine, the combination with a frame, of a drive shaft mounted in said frame, a wire feeding mechanism comprising a plurality of co-operating feeding cams, one of said cams secured to said drive shaft, the other of said cams operatively geared to said shaft, staple forming and driving mechanism positioned below and operatively connected to said drive shaft, a cutting mechanism positioned on one side of said staple forming and driving mechanism and actuated by the cam secured to said drive shaft for cutting the wire fed by said feeding mechanism, and means whereby said feeding mechanism and said cutting mechanism may be adjusted to vary the length of staples made by said stitching machine.

8. In a wire stitching machine, the combination with a frame, of a drive shaft mounted in said frame, a wire feeding mechanism comprising a plurality of feeding cams, one of said cams mounted on said drive shaft, the other of said feeding cams positioned above the first feed cam and geared to said drive shaft, staple forming and driving mechanism positioned directly below said wire feeding

mechanism, wire cutting mechanism positioned on one side of said staple forming and driving mechanism, and operative connections positioned in the path of one of said cams whereby said cutting mechanism is actuated to cut the wire fed by said feeding mechanism.

9. A wire stitching machine comprising a frame, a drive shaft mounted on said frame, a wire feeding member mounted on said frame and adapted to rotate concentrically with said shaft and driven thereby, a bracket pivoted to said frame and carrying a wire feeding member above said first named member, a staple forming and driving mechanism positioned directly below said first named feeding member and operatively connected with said shaft, and guiding means whereby the wire is fed by said feeding members to said staple forming and driving mechanism.

10. A wire stitching machine comprising a frame, a drive shaft mounted on said frame, a wire feeding member mounted on said frame and adapted to rotate concentrically with said shaft and driven thereby, a bracket pivoted to said frame and carrying a wire feeding member above said first named member, and a staple driving mechanism positioned directly below said first named feeding member and associated therewith in a manner to be driven thereby.

11. A wire stitching machine comprising a frame, a drive shaft mounted on said frame, a wire feeding member mounted on said frame and adapted to rotate concentrically with said shaft and driven thereby, a bracket pivoted to said frame and carrying a wire feeding member above said first named member, a staple forming and driving mechanism positioned directly below said first named feeding member, a cam mounted on said drive shaft for operatively driving said staple forming mechanism, and a pitman connection for connecting said first named feeding member and said staple driving mechanism for operatively driving said staple driving mechanism.

12. A wire stitching machine comprising a frame, a drive shaft mounted on said frame, a wire feeding cam mounted on and operatively driven by said shaft, a swinging bracket pivoted to said frame and having a wire feeding roller journaled therein, said wire feeding roller being operatively related to said shaft and co-operating with said first named cam for feeding wire between their surfaces, staple forming and driving mechanism positioned below said wire feeding mechanism, wire cutting mechanism positioned on one side of said staple forming and driving mechanism, means actuated by said wire feeding cam for actuating said cutting mechanism to cut the wire fed by said feeding mechanism, and means operatively connected to said shaft for actuating said staple forming and driving mechanism.

13. A wire stitching machine comprising a frame, a drive shaft mounted on said frame, a wire feeding cam mounted on and operatively driven by said shaft, a swinging bracket pivoted to said frame and having a wire feeding roller journaled therein, said wire feeding roller being operatively related to said shaft and co-operating with said first named cam for feeding wire between their surfaces, 5 staple forming and driving mechanism positioned below said wire feeding mechanism, means connecting said staple driving mechanism with said wire feeding cam for actuating said staple driving mechanism, and means for 10 operating said staple forming mechanism.

14. A wire stitching machine comprising a frame, a drive shaft mounted on said frame, a wire feeding cam mounted on and opera- 15

tively driven by said shaft, a swinging bracket pivoted to said frame and having a wire feeding roller journaled therein, said wire feeding roller being operatively related to said shaft and co-operating with said first named cam for feeding wire between their surfaces, 20 staple forming and driving mechanism positioned below said wire feeding mechanism, a pitman connection connecting said staple driving mechanism with said wire feeding cam for actuating said staple driving mechanism, and means mounted on said shaft for 25 operating said staple forming mechanism.
